(57) **CLAIM**

The ornamental design for an ultrasound probe, as shown and described.

DESCRIPTION

FIG. 1 is a right rear isometric view of an ultrasound probe showing our new design;

FIG. 2 is a left rear isometric view thereof;

FIG. 3 is a right side elevation view thereof;

FIG. 4 is a left-side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The dash-dot-dash broken lines and the dashed lines on the right side of the ultrasound probe adjacent to the shaded areas depict boundaries of the claim and form no part thereof. All other dashed lines in the drawings depict portions of the ultrasound probe that form no part of the claimed design.
